CLAIM

The ornamental design for an air hammer tool, as shown and
described.

DESCRIPTION

FIG. 1 is a perspective view showing my new design for an
air hammer tool;

FIG. 2 is a right side elevational view which is a mirror
image of the left elevational view;

FIG. 3 is a top plan view;

FIG. 4 is a bottom plan view;

FIG. 5 is a front elevational view; and,

FIG. 6 is a rear elevational view.

The broken line drawings of environmental structure are for
illustrative purposes only and form no part of the claimed
design.
